(57) **CLAIM**

I claim the ornamental design for a car seat protector, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of the car seat protector, showing my new design in a fitted configuration as installed on a car seat.

FIG. 2 is a front perspective view thereof, illustrated in flat configuration,

FIG. 3 is a rear perspective view of FIG. 2;

FIG. 4 is a left-side elevation view of FIG. 2;

FIG. 5 is a right-side elevation view of FIG. 2;

FIG. 6 is a top plan view of FIG. 1; and,

FIG. 7 is a bottom plan view of FIG. 1.

The broken lines in the figures represent stitching and are part of the claimed design.

To protect the backseats of a vehicle from being scratched, dented or marked by infant, baby or child booster seats.
